UNITED STATES PATENT OFFICE.

SAMUEL N. GOODMAN, OF PHILADELPHIA, PENNSYLVANIA, ASSIGNOR TO FRIED-BERGER-AARON MANUFACTURING COMPANY, OF PHILADELPHIA, PENNSYLVANIA, A CORPORATION OF PENNSYLVANIA.

DESIGN FOR A LACE-TRIMMING.

56,601.

Specification for Design.

Patented Nov. 16, 1920.

Application filed January 2, 1919. Serial No. 269,358. Term of patent 7 years.

To all whom it may concern:

Be it known that I, SAMUEL N. GOODMAN, a citizen of the United States, residing in Philadelphia, county of Philadelphia, and State of Pennsylvania, have invented a new, original, and ornamental Design for Lace-Trimming, of which the following is a specification, reference being had to the accompanying drawing, which forms a part thereof.

The design is more particularly adapted for embodiment in lace shoulder straps for ladies' underwear, although it is adapted for use as a trimming of any kind.

The figure is a plan view of a number of repeats of a lace trimming embodying my design.

The design comprises a relatively plain knit longitudinally extending central strip flanked along opposite edges by a series of arch-shaped scallops, each scallop comprising a series of loops, adjacent loops being tied together; the whole presenting the distinctive appearance shown.

I claim—

The ornamental design for lace trimming as shown and described.

In testimony of which invention, I have hereunto set my hand, at Philadelphia, on this 27th day of December, A. D. 1918.

SAMUEL N. GOODMAN.
